UNITED STATES PATENT OFFICE.

JOSHUA W. MAYER, OF NEW YORK, N. Y.

DESIGN FOR A RING OR SIMILAR ARTICLE.

57,245.

Specification for Design.

Patented Mar. 8, 1921.

Application filed October 14, 1920. Serial No. 417,057. Term of patent 7 years.

To all whom it may concern:

Be it known that I, JOSHUA W. MAYER, a citizen of the United States of America, residing at New York city, county and State of New York, have invented a new, original, and ornamental Design for a Ring or Similar Article, of which the following is a specification, reference being had to the accompanying drawing, forming part hereof, which represents in elevation a ring embodying my new design.

I claim:—

The ornamental design for a ring or similar article, as shown.

Signed at New York city, N. Y., this 11th day of Oct., 1920.

JOSHUA W. MAYER.

Witnesses:

DAVID KAISER,
MAURICE BLOCK.
